UNITED STATES PATENT OFFICE.

FREDERICK C. SMITH, OF WATERBURY, CONNECTICUT, ASSIGNOR TO WATERBURY MFG. CO., OF WATERBURY, CONNECTICUT, A CORPORATION.

LAMP-SHADE.

1,211,772.

Specification of Letters Patent.

Patented Jan. 9, 1917.

Application filed October 23, 1916. Serial No. 127,094.

To all whom it may concern:

Be it known that I, FREDERICK C. SMITH, a citizen of the United States, residing at Waterbury, in the county of New Haven and 5 State of Connecticut, have invented a new and useful Improvement in Lamp-Shades; and I do hereby declare the following, when taken in connection with the accompanying drawings and the characters of reference 10 marked thereon, to be a full, clear, and exact description of the same, and which said drawings constitute part of this application, and represent, in—

Figure 1 a top or plan view of a lamp shade constructed in accordance with my invention. Fig. 2 a transverse sectional view of the same. Fig. 3 a transverse sectional view at right angles to the position shown in Fig. 2. Fig. 4 a side view of the stud, 20 detached.

This invention relates to an improvement in lamp shades such as are commonly applied to the bulbs of incandescent lamps so as to be self-supporting thereon. These 25 shades consist of a shell with some clamping means for engaging with an electric light bulb.

The object of this invention is to provide with a shade so that the parts may be 30 finished before they are assembled and without the use of solder, which would injure the finish; and the invention consists in the construction as hereinafter described 35 and particularly recited in the claims.

In carrying out my invention, I employ a shell 5 which is struck up from sheet metal into semi-spherical form with an outwardly extending flange 6 at its edge. In 40 the center of the shell is a hole 7 in which is secured a stud 8, which stud is larger in diameter than the diameter of the hole 7, and provided with a reduced portion or neck 9 which will pass through the hole 7 and 45 upset outside the shell so as to interlock the stud with the shell. In the end of the stud is a slot 10 to receive the central swaged portion 11 of a wire yoke 12 each end of which is bent into ring shaped parts 50 which stand parallel with each other. The swaged portion of the wire-holder is inserted into the slot 10 and the end of the stud upset so as to firmly interlock the wire

holder stud, and hence lock it centrally in the shade beyond the edge of which the 55 rings project. The sides of the wire holder are adapted to be sprung over an incandescent electric lamp bulb, and so that the shade may be turned to any desired angle with relation to the bulb, it being held in 60 position by the friction of the wire holder. This construction permits the inside, as well as the outside of the shell to be finished by 65 buffing or otherwise before the parts are assembled, and the ring entered into the stud 70 and the end of the stud inserted through a hole in the shell and upset in a suitable press so as to interlock the wire-holder in the stud and interlock the stud with the shell, thus avoiding the use of solder the heat of which 75 would mar the finish of the inside or outside of the shell.

I claim:—

1. A lamp shade comprising a shell formed with a central opening, a stud larger 75 in diameter than said hole and formed with a neck adapted to extend through said hole outside of which it is upset, said stud also formed with a transverse slot, and a wire-holder entered into said slot the side walls 80 of which are compressed against the said holder.

2. A lamp shade comprising a metal shell formed with a flange and with a central hole, a stud larger in diameter than said hole 85 formed with a reduced portion adapted to extend through said hole and project beyond the outer surface of the shell upon which it is upset, whereby the stud is interlocked with the shell, said stud formed with 90 a transverse slot, combined with a wire holder swaged at its center to enter said groove in the stud, the walls of which are upset to interlock the holder with the stud, the ends of said holder projecting outward 95 from said stud and beyond the edge of the shell, the ends of the wire turned into ring-shape which are arranged parallel with each other.

In testimony whereof, I have signed this 100 specification in the presence of two subscribing witnesses.

FREDERICK C. SMITH.
